UNITED STATES PATENT OFFICE.

LEO M. CHAPMAN, OF CHICAGO, ILLINOIS.

LINE-CASTING MACHINE.

1,057,803.

Specification of Letters Patent.

Patented Apr. 1, 1913.

Application filed December 24, 1910, Serial No. 599,106. Renewed May 14, 1912. Serial No. 697,300.

To all whom it may concern:

Be it known that I, LEO M. CHAPMAN, a citizen of the United States, residing at Chicago, in the county of Cook and State of Illinois, have invented certain new and useful Improvements in Line-Casting Machines, of which the following is a specification.

My invention relates to improvements in line casting machines.

The general object of my invention is to provide an attachment to a matrix-assembling machine by the use of and reference to which intricate tabular matter may be set up in column arrangement with ease, accuracy, and rapidity, without the necessity of subsequent hand justification.

Another and more specific object of my invention is to provide an improved clutch mechanism for the assembler bar or slide, whereby said bar is more securely and positively held in place and is controlled on its return or backward movement against the assembled matrices to prevent jar and wear of the mechanism.

A still further object is to provide a means for displacing the star wheel, thereby preventing same from pounding the matrices and imparting unnecessary vibration to said assembler bar and the associated indicator, and further to prevent unnecessary wear of the parts.

Other and further objects of my invention will readily become apparent to persons skilled in the art from a consideration of the specification taken in conjunction with the drawings, wherein—

Figure 1 represents the frame of a well-known type of linotype machine, or a portion of the assembler mechanism thereof, with my improved device applied thereto; Fig. 2 is a rear view of a portion of said mechanism; Fig. 3 is a detailed view of the star wheel and my improved star-wheel-displacing attachment; Fig. 4 is an enlarged section taken on line 4—4 of Fig. 1; Fig. 5 is a similar view taken on line 5—5 of Fig. 1; Fig. 6 is an enlarged perspective view of the assembler bar mechanism; Fig. 7 is a

detent secured to the assembler bar for engagement with the indicating device; and Fig. 8 is a scale beam of the indicating device showing the application of the adjustable stops thereon.

In all of the views, the same reference characters indicate similar parts.

In carrying my invention into effect, I provide an improved indicator which directly determines, and indicates with accuracy, the number of spaces or points required to complete any portion of a line to a predetermined point within the line.

My indicator is especially adapted for use in conjunction with my improved assembler bar brake and star-wheel-displacing mechanism, although it may be used independently of these devices, but without the attending advantages produced by their co-operation.

While I contemplate describing a single embodiment of my invention, it is of course apparent that many variations in details within mechanical skill may be made therein without departing from the spirit and scope of the claims.

10 represents a frame of a linotype machine, or that portion thereof that is necessary to be shown for the purpose of disclosing the arrangement, use, and operation of my improved attachments in association therewith.

11 is the ordinary traveling belt for conveying the matrices 12 to the assembler bar 13 and against the rear upwardly projecting finger 14, secured to the front end of the assembler bar against which the matrices are delivered and by the star wheel are thereby forced into position, and said bar being thereby moved bodily to the left to make room for the incoming matrices which drop into place at the right hand end of the line adjacent to the star wheel 15. A spring-pressed arm 16 is connected to the assembler bar 13 by means of a link 16', which returns the assembler bar to its normal or retracted position after said bar has been released by the brake, as when the line has been completed and the matrices have

been removed from the assembling elevator in which they have been placed by the star wheel.

17 and 17' and 17'' are roller bearings 5 upon which the assembler bar is longitudinally reciprocated.

So far as referred to, the parts above described are of the well known linotype construction. In connection with such machines, I employ a simple and efficient indicating apparatus, by means of which the operator is informed at a glance of the number of space matrices, or combination thereof, that are required from a given point 10 to complete a line, or any portion of a line of assembled, non-compressible, or non-expansible, matrices and spaces, so as to correspond exactly with the line above or below said line, as in setting tabular matter or the 15 like.

The indicator consists of a supporting frame comprising a beam part 18, turned downwardly as at 19 and 20, to provide legs which are preferably slotted at their ends 20 for engagement with screws 21 and 22, whereby the said frame is fixedly secured to the frame 10 of a linotype machine. These screws are already provided in such a machine and are known as the assembler 25 slide stop screws and assembler slide roll bracket screws, and for convenience I make the frame, of my indicating device, of such dimensions as properly to engage said screws for the purpose of securing it to the frame. Secured to the beam 18 is a casing 23 containing a dial 24. The dial is divided into 30 twelve divisions, beginning at zero, at the top, and numbering clockwise to 8 and beginning at zero and numbering counterclockwise to 3, thus forming two scales the characters of which are arranged one after another at suitable intervals along the path of a relatively movable pointer but which are arranged to read in opposite directions 35 from a zero mark, said mark constituting in operation an indication that no more matrices are to be inserted in the line. Thus one scale is indicative of decreasing numbers of type points to be filled in the line and 40 the other scale is indicative of increasing numbers of type points actually filled beyond the intended length of the line. An indicating pointer 25, normally standing at 8, is adapted to sweep over the scales provided on the dial, being mounted on a central axis 26, to which is secured a pinion 27. A rack arm 28 is pivoted as at 29 to the beam 18. The upper end of the rack arm is provided with a segmental rack 30, which encages 45 the pinion 27 to rotate the indicator 25, such arrangement being one convenient form of motion-multiplying connections between a movable indicating part and a part to be moved in the operation of the assem-

bler slide. To the beam 18 is loosely attached a horizontal pica-M scale 31, reading from the right to the left and having teeth and notches cut into it upon its under surface or edge as at 31', and divided so as to indicate pica spaces and half-spaces. The 55 pica scale 31 is loosely attached to the frame end 19 by means of a screw 32 passing through said scale into the frame end 19, through an upwardly inclined slot 33 at the right hand end thereof, and at the opposite end the scale is pivoted to the lower end 34 of the arm 28, as at 35. The radius of the end 34 of the arm 28 corresponds with the inclination of the slot 33, so that when the scale 31 is moved to the left, it is also 60 thereby bodily raised uniformly at both ends, so that said pica scale moves upwardly a distance about one-half its horizontal movement, and when so moved the rack 30 of the arm 28 is correspondingly 65 moved around the pivotal point 29, whereby the indicating needle 25 is caused to sweep over the scale provided on the dial. In order that this movement may not be spasmodic, I may attach to the rack end 70 30, of the arm 28 a small extension arm 36 which carries one element of a retarding device, such as a dash pot 37. In this case, it is shown to carry the plunger 38 thereof, the pot portion of the device being attached to a fixed part of the indicating mechanism. A coiled spring 39 returns the rack arm 30 to the normal position shown in Fig. 1, and thereby the scale beam, 31, is likewise returned to its lowest and retracted position. The arrangement is such that a movement of the scale 31 of one pica-M to the left will move the indicating pointer just once around the dial; the dial being spaced off, or divided into twelve equal points 75 numbered clockwise on the right to eight, and counterclockwise on the left to three. Spring-pressed, adjustable positive stops 40, of which there may be any necessary number, there being three shown in Fig. 1, all 80 of which are similar in general construction, are adapted to be placed along the pica scale beam 31, at any desired position corresponding with the tabulation of the work to be done. These stops are adapted to be 85 placed at any selected point along the scale and are secured in position by the notches provided upon the under surface thereof. For convenience, I make the stops of two parts, 41 and 42, preferably held together 90 by a resilient spring 43. The lower part 41 carries a pin 45 which is adapted to enter any one of the notches between adjacent teeth provided on a pica scale 31. The teeth are so proportioned as to represent one-half 95 a pica space, so that when the pin 45 enters a notch the adjustable stop 40 indicates an even number of picas, and when it enters the 100

adjacent notch or space between adjoining teeth, it indicates a definite number of picas, and a fractional one-half pica. In Fig. 8, the stop is placed so as to indicate a number 5 of picas and one-half; therefore the stop 40 may be placed along the scale beam 31 in any selected position within a half pica of any particular point. By depressing the screw 44, the pin 45 is moved below the 10 lower edge of the pica scale beam, and the stop may be moved along the beam to any selected position. When released, the pin 45 will enter a space between teeth and securely hold the adjusted parts in such position. 15

Secured to the laterally reciprocating assembler bar 13 is a spring-pressed detent device, 46, the detent proper being pivoted as at 47, and supported by means of a spring 20 48. Further rearward movement is prevented by means of a stirrup 49, which surrounds the detent arm and is secured to a bar 50 by means of a pin 51. When the assembler bar 13 is moved to the left, the 25 front edge of the detent 46 will positively engage the adjustable stop 40 and move the pica scale bar 31 to the left and upwardly until said bar has been moved in an upward direction sufficiently to escape the upper 30 point of the detent 46. On the return of the assembler bar 13 to the right, or toward normal position, the detent 46 will be depressed against the spring by the adjustable stop 40, and permit said detent to pass by 35 said stop, after which the spring 48 will return it to normal position. The bar 50 is secured by means of the screw 52, to the assembler bar 13, so that the detent moves positively with the assembler bar on both of its 40 excursions. When the detent strikes one of the adjustable stops 40, of which there may be several on the scale, placed as desired, it immediately moves the pica bar or scale to the left, and thereby the indicating needle 45 25 is moved over the dial in a perfectly obvious manner, and will stop at some position between eight and zero. When the needle 25 is moved to the right and stopped at a given point, it thereby immediately indicates to 50 the operator the number of points required to be inserted between the matrices already assembled and some objective point in the line, and when the proper indicated number of points have been included in the line with 55 the matrices, the needle will then move to zero and stop, showing proper justification. If a less number of blank matrices or points than required are placed in the line, with the character matrices, it will move to a position 60 short of the zero, or say to point two, which will indicate that a two point matrix blank is necessary to fill out the line before the objective point is reached. If a greater number of points have been included with the as-

sembled matrices than is required, the needle 6 will move beyond zero to 1, 2, or 3, as the case may be, indicating to the operator that the intervening space has been filled to a greater extent than is required. The assembler bar will continue to move to the left 70 while other matrices are being assembled in the line, and the pica bar 31 will have moved upwardly out of contact with the detent 46, and the detent will therefore pass to the left of the said adjustable stop and permit the 75 pica scale bar 31 to return to its lowest position, and coincidently with the needle 25 on the dial 24. After such return, the detent may come in contact with another adjustable stop in the same line, and the same performance will be repeated. Just before the termination of a line, the final and last adjustable stop may be encountered by the detent, which will indicate to the operator the necessary number of points to be included with 80 the matrices before reaching the end of the line. The crowding of the matrices into position by the operation of the star wheel 15 is the means by which the assembler bar is moved to the left against the resistance of 85 the returning spring exerted on the rod 16.

When the assembler bar 13 is moved to the left by the introduction of the matrices, it is necessary to hold it in the position it has so been placed. I therefore provide a brake 95 mechanism for this purpose. This device is more clearly shown in Fig. 6, and consists of a bell crank lever 54, pivoted as at 55, and provided with an adjusting screw 58 upon its horizontal arm 59, its upper arm 60 being provided with a thumb piece 61, by which it may be manually moved. A brake shoe 62 is pivotally and loosely secured to the arm 60, as by a screw 63. The screw 63 is preferably placed in the arm 60 a little 100 to the right of the central vertical line. Another shoe 65 is loosely secured to the arm 60 by means of a screw 66, which is placed a little to the left of the central vertical line of the arm 60. The latter shoe 65 is provided 110 with a tail-piece 67, to the lowest end of which is secured a spring 68. The other end of the spring 68 is secured to a longitudinal link 69, which has slotted lost-motion connection with the arm 60, as at 70, the other end of the link 69, being connected to a bell crank lever 71, as at 72, the bell crank 71 being connected to a link 72', leading to a finger lever 73. The crank lever 71 is yieldingly held in place and the key lever raised, 115 by means of spring 74. When the key 73 is depressed, the link 69 is moved laterally, and when said key is sufficiently depressed, it moves the bell crank lever 54 on its pivot 55 for the purposes of releasing the brake. 120

Referring now to Fig. 2, it will be observed that the bell crank lever, 75, is pivoted as at 76, the lower arm 77 of which is 125

connected to the link 69 as at 78, the upper arm 80, being provided with an adjustable set screw 81, being held in its downward position by means of the open spiral spring 83 acting through arm 82 of a gear-carrying bell crank lever. The arm 82 is pivoted, as at 84, on an axis which carries the gear wheel 85 that meshes with a gear wheel, 86, that drives the star wheel 15. The arm 82 is limited in its movements by a slot 87, provided in the fixed part of the frame of the machine, the shaft of the star wheel operating in said slot 87 so that arm 82' and consequently arm 82 of the bell crank lever may not move a greater distance than the length of said slot. The gear wheel 85' drives the train. As shown in the position of Fig. 2, the star wheel 15 is in its operative position so as to make engagement with the matrices as they come down from the chute into place and force them into their proper assembled relation. When the arm 82' is depressed and the arm 82 is raised against the resilient effort of the spring 83, the star wheel is thereby withdrawn or displaced from its position of engagement with the matrices and no longer is permitted to make forcible contact therewith, and therefore the assembler bar is not violently agitated or vibrated by the constant pounding of the star wheel against the assembled matrices. The constant pounding of the star wheel against the surfaces of the assembled matrices produces disagreeable and objectionable vibration of the assembler bar, thereby causing the needle of the indicating device to vibrate excessively to such an extent as to be practically unintelligible. As clearly shown in Fig. 2, the assembler bar is included between the clutch 62 and 65 of my braking device, and the arrangement is such that the shoes will clamp the assembler bar and permanently and fixedly hold it in any position in which it has been placed by the star wheel upon the introduction of the assembled matrices.

The use and operation of my device is as follows: After the indicating instrument has been placed and secured on the machine as by screws 21 and 22, the detent 46 is to be secured to the traveling slide, or assembler bar, in any convenient manner in such relation to the adjustable stops 40 on the pica scale that it will come into contact with the lower part of such stop in its reciprocating movements. As the detent is moved in a path below the pica scale beam, it may be brought into contact with several of the adjustable stops which may be placed upon the said scale beam at points suitable to notify the operator of the space to be filled between the matrices that have already been assembled and some objective point within the line. As the pica beam is thus moved to

the left, it is also raised by virtue of the inclined slot 33, so that the beam operates the arm 28, which by virtue of its geared engagement with the indicator hand or pointer, 25, moves the latter over the scale provided on the dial, thereby indicating to the operator the space or spaces necessary to be filled in the line, or that portion of the line between the matrices already assembled and some objective point corresponding with a similar point in the line above, as in tabular work. As the matrices fall into the carrier, the star wheel 15 presses the slide by its contact with the matrices to the left, and the brake mechanism, shown in detail in Fig. 6, clamps the assembler bar or slide between its brake-shoes 62 and 65, and holds the slide or assembler bar in the position into which it has been placed by means of the star wheel. If any irregularities in the assembling of the matrices occur, due to vibration of the star wheel or improper working of the brake, and the assembler slide is forced too far forward, thus causing the indicating needle to show less spaces or points needed to complete any given portion of the line than is actually the case, this fault may be corrected by operating the finger key 73, thereby pulling on the link 69, and moving the bell crank lever 77, which lifts the pivoted arm 82 against the resilient spring 83, thereby depressing the arm 82', carrying the star wheel, and removing or displacing it from its operative position. It will be observed that the arm 82', simply moves the gear wheel 86 out of its normal position, the shaft of gear wheel 86 simply carrying the star wheel 15 around the gear 85, and not out of mesh therewith, but sufficiently to displace the star wheel from its active cooperation with the assembled matrices. The link 69 has lost motion connection with the bell crank 54, as at 70, and further depression of the finger key 73 will move the vertical arm 60 of the bell crank lever 64 so as to move the pivotal points 63 and 66, carrying the respective brake shoes 62 and 65, into a substantially vertical line, thereby releasing the assembler bar or slide from the gripping braking effect of the shoes thereon. At the same time, tension is applied to the spring 68, and the shoe 65 is yieldingly held against the surface of the under side of the assembler bar, thereby permitting the assembler bar to return to its normal position under control of the operator, and preventing the sudden impact of the bar with the stationary portions of the machine at the end of its excursion. When the star wheel has been displaced from operative position, in the manner described, the assembler bar can return with the matrices that have been assembled in front hereof, and thereby any indication, noted by the pointer on the indi-

eating device, will be clearly apparent. At any time during the operation of the device, independently of whether or not the lines have been completed, the brake may be released in the manner described, and the beneficial results arising from the displacement of the star wheel will be attained.

Having thus described an embodiment of my invention, what I claim is:

10 1. In a machine of the class described, an assembler slide, a star wheel normally held in position to strike the matrices into position and move said slide and means for temporarily displacing said star wheel from 15 such normal position to prevent further vibration of the slide incident to the strokes of the star wheel.

2. In a machine of the class described, an assembler slide, a bodily movable star wheel 20 for placing the matrices and for moving said slide, a brake for said slide, and means for releasing said brake and displacing said star wheel from operative position.

3. In a machine of the class described, an assembler slide, yielding means for returning said slide to normal position, a star wheel for moving said slide against said yielding means as the matrices are assembled, a brake for holding said slide, and 30 means for displacing said star wheel from operative position, for releasing and for controlling said slide during the retracted movement.

4. In a machine of the class described, an assembler slide, a star wheel for placing the matrices and for moving said slide, a train of gearing for rotating said star wheel, yielding means normally maintaining said star wheel in operative position with respect to said slide to coöperate with matrices fed to the machine, and means for temporarily displacing said star wheel from such normal operative position of coaction with said matrices without disturbing the operation of said gear train to rotate said star wheel.

5. In a machine of the class described, having an assembler slide movable in one direction as the matrices are assembled and 50 in the opposite direction by a spring, in combination with a brake device for said slide comprising a pivoted lever carrying two loosely pivoted brake shoes for engagement with the opposite sides of said slide, a spring associated with the pivoted lever, and an independent spring associated with one of said brake shoes.

6. In a machine of the class described, having an assembler slide movable in one direction as the matrices are assembled and in the opposite direction by a spring, in combination with a brake device for said slide comprising a pivoted lever carrying two loosely pivoted brake shoes for engage-

ment with the opposite sides of said slide, 65 one of said shoes provided with a spring, and means for increasing the tension of said spring when the brake is released to retard the returning movement of said slide.

7. In a machine of the class described, 70 having an assembler bar movable in one direction as the matrices are assembled and in the opposite direction by a spring, in combination with a brake device for engaging said bar comprising an arm with an extended brake shoe loosely pivoted thereto on each side of the assembler bar, for gripping the bar, means for moving said arm for releasing the brake, and for yieldingly holding one of said shoes in contact with 75 said bar to cause said bar to return slowly.

8. In a machine of the class described, having an assembler bar in combination with a bodily movable star wheel for placing the matrices, a brake for said assembler 85 bar, a friction attachment for retarding the movement of said bar when the brake is released, and means for potentiating said friction attachment, bodily displacing said star wheel from operative position and for re- 90 leasing said brake.

9. In a machine of the class described having assembler mechanism for a line of matrices, of a pica scale beam, an adjustable stop thereon, a member movable with said assembler mechanism to engage said stop, and an indicator operable by said beam 95 upon said engagement.

10. In a machine of the character described having assembler mechanism for a 100 line of matrices, of an indicator having a pica scale beam, a dial having an index, means between said scale beam and index to operate the latter, an adjustable stop on said scale beam to engage a part of the 105 assembler mechanism, and a detent carried by said mechanism for engaging said adjustable stop.

11. In a machine of the class described, having an assembler mechanism for a line 110 of matrices, of an indicator having a slideable pica scale beam, an adjustable stop movable to selected position on said beam, an index operable by the movement of said beam, means carried by said assembling 115 mechanism for engaging said adjustable stop, and means for releasing said engagement upon further progress of the assembling mechanism.

12. An indicating apparatus, for a machine of the class described comprising assembler mechanism, a part movable thereby, an index having a dial and carrying a rotary needle in coöperation with the dial, a movable pica scale beam, an adjustable stop, 125 shiftable to selected positions on said beam for engagement by the laterally movable part to be operated by the assembling mech-

anism, and means connecting said beam and needle to rotate the latter when said beam is moved laterally and upwardly by the assembling mechanism.

13. In a machine of the class described, the combination with an assembler slide movable in one direction as the matrices are assembled and in the opposite direction by a spring, said assembler slide providing an upper and an under straight brake-receiving surface, an upper and a lower brake shoe respectively cooperating with said upper and lower surface, each said shoe providing a straight flat surface for coaction therewith, a member to which said shoes are pivotally mounted, each to adjust itself automatically for equal pressure against said slide surface throughout said flat surface of the shoe, said member being movable to clamp the slide between the straight portions of the shoes, and to loosen such grip, and means to operate said member.

14. In a machine of the class described, an assembler bar arranged to be moved in harmony with the size of the matrices inserted, indicator means adapted to indicate the movement of the assembler bar toward a predetermined point in its movement, means to operate the indicator comprising a detent movable with the assembler bar, a pica scale beam, and a stop associated with the indicator, said detent and stop arranged to engage at another predetermined point in the movement of said assembler bar, said stop being adapted and arranged to move with the detent in the direction of detent movement to cause indication of subsequently inserted matrices, and one of said engaging parts being movable out of engagement with the other after a predetermined movement of said parts together.

15. In a device of the class described, an assembler bar arranged to be moved in one direction by the matrices, and in the opposite direction to return the parts to normal position, indicator means to indicate type points, and means to operate said indicator means comprising a detent movable with the assembler bar, a scale beam and a stop associated with the indicator means, said stop located to be engaged and moved by the detent to indicate type points, and one of said parts being movable out of engagement with the other upon the return movement of said assembler bar.

16. In a machine of the character described having movable assembler mechanism for a line of matrices, an indicator having a relatively movable scale and pointer, a graduated pica scale, and a part adjustable on the pica scale to effect operative connection between the relatively movable element of the indicator, and the assembler mechanism at the point in the

travel of the assembler mechanism indicated by the adjustment of said part on the pica scale.

17. In a machine of the character described having movable assembler mechanism for a line of matrices, an indicator having a relatively movable scale and pointer, a graduated pica scale, a part adjustable on the pica scale, for operative connection with the movable assembler mechanism and connecting means between said movable element of said indicator and said pica scale whereby said indicator means is moved one complete cycle of its excursion while said pica scale is moved the distance of one of its divisions.

18. In a machine of the character described having movable assembler mechanism for a line of matrices, an indicator having a relatively rotatable scale and pointer, a longitudinally movable, graduated pica scale, a part adjustable on the pica scale for operative connection with the movable assembler mechanism, and motion-multiplying connecting means, between said rotatable indicator element and said graduated pica scale by means of which the longitudinal movement of the latter is converted into rotary movement of the former whereby said indicator element will complete one revolution upon the longitudinal movement of said scale equal to a space occupied by a pica em.

19. In a machine of the character described having movable assembler mechanism for a line of matrices, an indicator having a relatively movable scale and pointer, a motion-multiplying mechanism connected with the moving elements of said indicator, and means including a scale and independently adjustable members thereon for connection of said assembler mechanism at points in its forward movement with said indicator moving mechanism, whereby to indicate, in relatively long gradations, the movements of said assembler mechanism.

20. In a machine of the character described having movable assembler mechanism for a line of matrices, a frame for supporting a movable pica scale beam and an indicator thereon, and attaching means on said frame suitably spaced apart, for supporting engagement with screws known as the assembler slide stop screw and the assembler slide roll bracket screw, of said machine.

21. An indicating attachment for a matrix assembling line casting machine comprising a frame having mounted thereon a graduated pica beam, movable longitudinally and vertically; an adjustable stop on said beam for engagement with a movable part of said machine, an indicator having a relatively movable scale and pointer on said frame

and a motion-multiplying mechanism connecting said beam and moving part of the indicator whereby the latter will be moved during the longitudinal and vertical movement of the former.

22. In a machine of the character described having assembler mechanism movable toward and thereafter beyond certain predetermined positions in the travel thereof, an indicator having characters to form two scales and a pointer for said scales, said scales and said pointer being relatively movable, a means for each of said certain predetermined positions in the travel of the assembler mechanism for causing indicating movement of said relatively movable scales and pointer by movement of the assembler mechanism, said scales reading from a common zero increasingly upward in opposite directions, said scale being arranged, with respect to said means for moving the same, for correspondence between said zero mark of the scales and each said predetermined position of the assembler mechanism, whereby said pointer in its entire traverse of said indicator may indicate the location of said assembler mechanism in the predetermined position thereof, or the location of said assembler mechanism an indicated number of steps either beyond or in front of said predetermined position.

23. In a machine of the character described having assembler mechanism movable toward and thereafter movable beyond predetermined positions in the travel thereof, the combination of an indicator adapted and arranged to show decreasing indications and thereafter increasing indications in type points, all by a limited movement of the assembler slide at any selected position in the movement of said slide, and normally inoperative means adapted and arranged to connect said slide and indicator, said means being operative between points in the travel of said slide respectively in front of and beyond the selected position to be indicated, that point which lies in front of said selected position corresponding to the highest of said decreasing indications and that point which lies beyond said selected position corresponding to the highest of said increasing indications, for purposes described.

24. In a machine of the character described, having movable assembler mechanism for a line of matrices, of an indicating device comprising relatively movable indicator parts, a movable scale beam, and means for relative movement of said indicator parts by the assembler mechanism including an adjustable stop on said beam.

25. In a machine of the character described having movable assembler mechanism for a line of matrices, of a scale beam, an adjustable stop therefor, an adjustable

detent for engaging said stop upon movement of the assembler mechanism, an indicator operable upon engagement of said stop and detent upon movement of said mechanism, and means for automatically releasing engagement of said parts at a predetermined point upon further advance of said mechanism.

26. In a machine of the character described having movable assembler mechanism, of a movable beam, an adjustable stop therefor, a detent movable by the assembler slide, means for locking said stop on said beam at any selected position and in position to engage said detent movable by the assembler mechanism, an indicator, and means intermediate said beam and indicator for operating the latter upon engagement of said stop and detent.

27. In combination with a machine of the character described having a movable assembler slide, a graduated dial; a relatively movable pointer for same, adjustable mechanism intermediate said slide and pointer located in the line of movement of a part carried by said slide, said pointer and dial arranged to show decreasing indications in type points when moved by said slide to a predetermined point in its movement and increasing indications in type points after passing said predetermined point in the travel of the slide, means for automatically releasing engagement between said slide and intermediate mechanism and means for returning said pointer and the intermediate mechanism to their normal positions upon further advance of said slide.

28. In combination with a machine of the character described having a movable assembler slide, of an indicator, operable by the movement of said slide, adapted and arranged to show decreasing indications in type points as the slide advances, a brake for said slide and a bodily movable star wheel for assembling the matrices, and moving the slide and means for moving said star wheel out of contact with the assembled matrices and operating said brake whereby the assembled matrices will be held compact and without vibration by said wheel that the indicator may become stable to clearly show the number of type points required to be inserted in the line of matrices to make the line the predetermined length.

29. In a machine of the character described, the combination of an indicator, movable assembler mechanism, and means for operation of said indicator by the assembler mechanism comprising a pica scale, a plurality of members adjustable on the pica scale to any points thereon in any desired relation to each other, and a member for successive engagement of said adjustable members during movement of the assembler

mechanism, one of said coacting members being adapted and arranged to disengage from the other upon movement of the assembler mechanism a predetermined relatively short distance for engagement of the next adjustable member by said coacting member.

30. In a machine of the character described, having a movable assembler mechanism, an indicator comprising a scale having thereon consecutively increasing indications, another indicator comprising a scale

and means for indicating consecutively decreasing graduations, motion-multiplying connections between said indicators, and means for operation thereof controlled by the assembler mechanism.

In testimony whereof I hereunto set my hand in the presence of two witnesses.

LEO M. CHAPMAN.

In the presence of—

MARY F. ALLEN,
W. LINN ALLEN.
